(57) **CLAIM**

The ornamental design for a scalpel handle, as shown and described.

DESCRIPTION

FIG. 1 is a left-side perspective view of a scalpel handle showing my new design;

FIG. 2 is a right-side perspective view thereof;

FIG. 3 is enlarged front elevational view thereof; and,
FIG. 4 is a enlarged rear elevational view thereof.

The broken line showing of the coupling section for a detachable blade is for illustrative purposes only and forms no part of the claimed design.
